UNITED STATES PATENT OFFICE.

THOMAS H. GAINES, OF HOPKINSVILLE, KENTUCKY.

CHURN.

1,082,513.

Specification of Letters Patent.

Patented Dec. 30, 1913.

Application filed April 29, 1913. Serial No. 764,464.

To all whom it may concern:

Be it known that I, THOMAS H. GAINES, a citizen of the United States, residing at Hopkinsville, in the county of Christian and State of Kentucky, have invented a new and useful Churn, of which the following is a specification.

This invention relates to churns and more particularly to dasher operating mechanism designed for use in connection with jars such as used extensively in the manufacture of butter.

One of the objects of the invention is to provide improved means whereby the structure constituting the present invention can be applied readily to a jar and securely fastened thereto, the said mechanism including stationary and revoluble dasher members which are insertible into the jar, and operate to thoroughly break the fatty globules and thus expedite the formation of butter.

A further object is to provide an attachment of this character all working parts of which are carried solely by a cap adapted to be placed upon the jar or other receptacle so that there are no bearings or joints which will be submerged in the cream.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a view partly in section and partly in elevation of the apparatus applied to a jar body. Fig. 2 is a side elevation of the attachment constituting the present invention.

Referring to the figures by characters of reference 1 designates a disk-like cap having brackets 2 secured thereto preferably at diametrically opposed points, these brackets being extended downwardly from the cap and having clamping screws 3 extending through the lower end portions thereof, each clamping screw being swiveled within a jaw 4. These jaws are adapted to engage the upper end portion of a jar A so that, when the jaws are tightened against the jar, as

shown in Fig. 1, the brackets 2 will pull downwardly upon the cap 1 and cause it to bear tightly on the jar. The cap is preferably provided with a gasket 5 of rubber or other suitable material which bears on the upper end of the jar and serves to seal the jar when the cap 1 is tightened in the manner described.

Secured upon cap 1 is a plate 6 having a sleeve 7 which extends downwardly through the center of the cap. This sleeve constitutes a bearing for a central dasher shaft 8 the upper end of which is provided with a bevel gear 9. This gear meshes with a larger drive gear 10 secured to a shaft 11 which is journaled within a bearing 12 extending upwardly from the plate 6. Shaft 11 may be rotated in any preferred manner, as by means of a crank 13. A housing 14 is detachably secured on the plate 6 and serves to inclose the gear 9, and the shaft 8 extends through the top of this housing as shown.

Extending radially from the shaft 8 are dasher blades arranged preferably in pairs. As shown in the drawings three of these pairs may be provided, the blades of the upper and middle pairs 15 being pitched so as to direct the cream downwardly during the rotation of the shaft 8. The blades of the lower pair 16, however, are pitched in the opposite direction so that, during the rotation of shaft 8, the cream will be directed upwardly by the blades 16.

A cross strip 17 is secured to the bottom of the cap 1 and extending downwardly from the ends of this cross strip are hangers 18 provided with inwardly extending retarding blades 20. These blades extend between the paths of the blades 15 and 16. It is to be understood that the blades 15 and 16 are arranged spirally about shaft 8.

In using the apparatus the jar or receptacle A is partly filled with the cream after which cap 1 is placed in position on the jar and the jaws 4 are clamped upon the jar so as to bind the gasket 5 onto the jar and thus seal the same. Shaft 11 is then rotated and motion will be transmitted therefrom through gears 10 and 9 to the shaft 8 and said shaft will be rotated at a high speed. During this rotation of the shaft, the blades 15 will operate to drive the cream downwardly toward the bottom of the receptacle A while the lower blades 16 will operate to throw the cream upwardly. Thus the cream will be thoroughly agitated by

reason of the conflicting up and down currents which are set up. Furthermore a whirling action is imparted to the entire body of cream but such action is retarded by the inwardly extending blades 20. This results in still further agitation of the cream. It will be apparent of course that as a result of this thorough agitation due to the peculiar action of the blades 15 and 16 and the retarding action of the blades 20, the globules of cream will be thoroughly broken up and the formation of butter will be expedited.

The device constituting the present invention can be easily applied to jars already in use and attention is called to the fact that all bearings and joints are located at points above the level of the liquid contents of the jar or receptacle A. When the cap 1 is removed, all parts of the mechanism are removed therewith and these parts can be easily reached for the purpose of cleaning and repairing them.

As the cap 1 fits tightly in position by means of the provision of gasket 5, splashing of the contents of the receptacle A is prevented.

What is claimed is:—

1. The combination with a cap, and a bearing element arranged therein, of a cross strip upon the lower face of the cap, hangers integral with the cross strip and insertible into a churn body, means extending through the bearing, cross strip and cap for fastening them together, a shaft journaled within the bearing and depending from the cap, said shaft and hangers being free at their lower ends, inwardly extending blades upon the hangers and in the same plane with the shaft, the blades on one hanger being in alinement with the corre-

sponding blades on the other hanger, and upper and lower blades revoluble with the shaft and between the blades on the hanger, the lowermost blades on the shaft being pitched to produce an upward current of liquid and the upper blades on the shaft being pitched to produce a downward current of liquid during the rotation of the shaft in one direction. 50

2. The combination with a cap, and a bearing element arranged therein, of a cross strip upon the lower face of the cap, hangers integral with the cross strip and insertible into a churn body, means extending through the bearing, cross strip and cap for fastening them together, a shaft journaled within the bearing and depending from the cap, said shaft and hangers being free at their lower ends, inwardly extending blades 60 upon the hangers and in the same plane with the shaft, the blades on one hanger being in alinement with the corresponding blades on the other hanger, upper and lower blades revoluble with the shaft and between the 65 blades on the hanger, the lowermost blades on the shaft being pitched to produce an upward current of liquid and the upper blades on the shaft being pitched to produce a downward current of liquid during the rotation of the shaft in one direction, means 70 mounted on the cap for rotating the shaft, and means carried by the cap for engaging the mouth portion of a jar to secure the cap upon the jar. 75

In testimony that I claim the foregoing as my own, I have hereto affixed my signature in the presence of two witnesses.

THOMAS H. GAINES.
